WRIST WATCH MOVEMENT HOLDER

Roy W. Argo, Muskegon, Mich.

Application May 2, 1938, Serial No. 205,610

2 Claims. (Cl. 81—6)

This invention relates to watch movement holders, and its general object is to provide a holder that is primarily designed for supporting and clamping a wrist watch movement, regardless of the size and shape thereof, in a manner whereby the holder sets up an automatic clamping engagement, with sufficient pressure against the movement, without damage thereto, yet the holder with the movement therein can be readily handled, and the movement worked upon, without any possibility of casual displacement or removal of the movement therefrom.

A further object is to provide a wrist watch movement holder in which the movement can be applied and removed with respect thereto, in an easy and expeditious manner, in that the holder includes slidably mounted spring actuated movement receiving jaw members normally held in clamping association and which are shaped and adjustable to fit movements of all sizes.

Another object is to provide a wrist watch movement holder that supports a movement in a manner whereby either side thereof can be readily inspected and worked upon, without removing the movement from the holder.

A still further object is to provide a wrist watch movement holder that is simple in construction, inexpensive to manufacture, and extremely efficient in use, operation and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a plan view illustrating one of the movement receiving faces of the holder and with the latter partly open.

Figure 2 is a plan view illustrating the other or opposite face.

Figure 3 is a side view looking toward the front of Figure 2.

Figure 4 is an end view looking toward the right of Figure 2.

Figure 5 is a sectional view taken approximately on line 5—5 of Figure 1, looking in the direction of the arrows.

Figure 6 is a sectional view taken approximately on line 6—6 of Figure 1, looking in the direction of the arrows.

Referring to the drawing in detail, it will be

noted that my holder is of substantially oval shape in outline, and includes four identical jaw members, indicated respectively by the reference numerals 1 to 4 inclusive, the jaw members being in the form of elongated blocks having bodies 5 of 5 arcuate formation in cross section.

Each of the jaw members have soldered or otherwise secured to the confronting outer faces of the bodies thereof, strip arms arranged in companion pairs which for distinction are indicated 10 by the reference numerals 6 and 7. The strip arms of each pair are slidably mounted on each other, and the strip arms 6 are bent at their point of connection with the bodies of their jaw members at right angles thereto and have flat sleeves 8 15 formed on the bent ends. The strip arms 7 are likewise bent at their point of connection with the bodies of their jaw members, at right angles, to provide fingers 9 slidably mounted in the sleeves 8 and the fingers have their outer ends inwardly 20 flared as shown in Figures 1 and 2, to prevent movement of the fingers from the sleeves, as will be apparent. The sleeves are preferably of a size to snugly fit the fingers to set up a frictional engagement therewith to hold the jaws in ad- 25 justed positions in the direction of the transverse axis of the holder.

Apertured ears 10 are formed on the confronting outer faces of the bodies of the jaw members, to receive coil springs 11, one of which has its ends 30 connected to the ears 10 of the jaw members 1 and 2 and the other coil spring has its ends connected to the ears of the jaw members 3 and 4, and it will be obvious that the coil springs urge the jaw members together in clamping association.

Due to the connection of the strip arms with the bodies in the manner as previously set forth, it will be obvious that an outward pull upon the sleeves 8 will cause the jaw members to separate along the longitudinal axis of the holder, and against the action of the coil springs 11, and the jaw members are movable along the transverse axis of the holder toward and away from each other, due to the slidable connection of the fingers 9 in the sleeves 8, consequently it will be 45 apparent that the jaw members are adjustable to fit watch movements of various sizes.

It will be noted that the upper faces of the bodies 5 when the holder is arranged as shown in Figure 1, are beveled or dished as at 12 and 50 formed on and rising from the outer corners of the upper faces are jaws 13 providing movement receiving shoulders 14 that incline inwardly from the confronting faces of the jaw members to the outer faces thereof, as best shown in Figure 55

1, and the jaws 13 are recessed as at 15 to provide movement receiving shoulders 16, adjacent the outer edges of the jaws 13, it being obvious that the shoulders 16 are adapted to receive a 5 larger movement than the shoulders 14.

The opposite or bottom faces of the bodies are likewise beveled or dished as at 17, but the beveled portions 17 are much smaller than the beveled portions 12 in order to provide relatively 10 large jaws 18 that are shouldered as at 19 and 20 to receive watch movements of different sizes, and due to the shape of the shoulders 14, 16, 19 and 20, and the fact that the jaw members are 15 adjustable with respect to each other, it will be obvious that my holder is capable of receiving, supporting and clamping watch movements of any shape and size, and in a manner whereby 20 the movement can be readily worked upon without fear of casual removal or displacement with 25 respect to the holder.

In the use of my holder, the jaw members are 30 adjusted transversely of the holder by sliding the fingers through the sleeves 8 until the desired size is obtained, thence the sleeves 9 are gripped and pulled outwardly for separating the 35 jaw members longitudinally of the holder, against the action of the springs. The watch movement is then seated on the desired shoulders, and the holder is then released for allowing the springs 40 to pull the jaw members together, so that they will set up a clamping engagement with the movement.

It is thought from the foregoing description 35 that the advantages and novel features of the invention will be readily apparent.

It is to be understood that changes may be 40 made in the construction and in the combination and arrangement of the several parts, provided that such changes fall within the scope of the appended claims.

What I claim is:

1. A watch movement holder comprising jaw members in the form of elongated blocks including bodies of arcuate formation in cross section, means for connecting the jaw members together in substantially oval formation and for adjustment toward and away from each other in the direction of both the longitudinal and transverse axes thereof, frictionally associated means included in the connecting means for holding the 5 jaw members in adjusted positions in the direction of the transverse axis thereof, means for urging and normally holding the jaw members in clamping association, jaws formed on the bodies, and movement receiving shoulders formed 10 on the jaws.

2. A watch movement holder comprising jaw members in the form of elongated blocks including bodies of arcuate formation in cross section, means for connecting the jaw members together 20 in substantially oval formation and including a strip arm for each jaw member and secured thereto, said arms being arranged in pairs with the companion arms of the pairs slidably mounted on each other for movement of the jaw members toward and away from each other in the 25 direction of the longitudinal axis of the holder, fingers formed on one pair of arms, sleeves secured to the other pair of arms and receiving the fingers for slidable movement therein for 30 movement of the jaw members in the direction of the transverse axis of the holder, said sleeves frictionally receiving the fingers for holding the 35 jaw members in adjusted positions in the direction of the transverse axis, springs for drawing the jaw members together in the direction of the longitudinal axis, and shouldered movement receiving jaws formed on the bodies.

ROY W. ARGO. 40
